UNITED STATES PATENT OFFICE.

HERBERT H. GERDING, OF NEWPORT, AND EDWARD A. GERDING, OF FORT THOMAS, KENTUCKY.

BOTTLE CRATE.

Application filed March 30, 1925. Serial No. 19,401.

To all whom it may concern:

Be it known that we, HERBERT H. GERDING and EDWARD A. GERDING, citizens of the United States, residing, respectively, at 5 Newport and at Fort Thomas, in the county of Campbell and State of Kentucky, have invented certain new and useful Improvements in Bottle Crates, of which the following is a specification.

10 Our invention relates to reinforced crates or boxes, and more especially to crates or boxes of composite wood and metal construction, such, for example, as are used for carrying and storing milk bottles. Its ob-

15 ject is to simplify and increase the effectiveness of construction of such devices, whereby they may be constructed with a minimum of expense for material and labor and be rigid and durable enough to withstand the 20 severe usage to which such crates, boxes or the like are usually subjected. Other objects will appear in the course of the ensuing description.

We attain these objects by the device 25 illustrated, for example, in the accompanying drawings, in which—

Figure 1 is a general perspective view 30 of a milk-bottle crate embodying our invention, part of the near side and parts of the interior construction being broken away better to reveal the interior corner construction;

Fig. 2 is a detail perspective view of one 35 of the outer corner members;

Fig. 3 is a similar view of one of the inner corner members;

Fig. 4 is a partial horizontal cross-section 40 on the plane of the line 4—4 of Fig. 5;

Fig. 5 is a partial vertical lengthwise section 45 on the plane of the line 5—5 of Fig. 4; and

Fig. 6 is a partial perspective view corresponding to Fig. 1, showing a modification.

45 In the example of Fig. 1, each side wall 1 is made up of a bottom slat 2, two intermediate slats 3, and a top slat 4; and each end wall 5 is made up of a bottom slat 6, two intermediate slats 7, and a top slat 8.

All of the slats are spaced apart vertically; 50 and the upper two slats 3 and 4, or 7 and 8, are spaced far enough apart to admit the hands between them, so that the end wall top slats 8 may be grasped as handles, in lifting the crate. The other slats preferably 55 are not spaced so far apart, and the three lower ones are considerably wider.

Each side slat overlaps the end of the corresponding end slat, at each corner of the 60 crate (Fig. 4). Usually it has been necessary to nail the boards or slats together at the corners, in prior crates. We avoid nailing by combining with the wooden slats suitable outer and inner sheet metal corner members. The outer corner member 9 (Fig. 65 2) is pressed into the shape of an angle bar with top and bottom inturned flanges 10 integral with the respective legs of the angle and with each other and adapted to overlap the top and bottom edges of the side and 70 end wall slats 4 and 8 and 2 and 6, respectively, when the corner member 9 fits snugly against the outer surfaces of the slats.

At suitable intervals, the legs of the angle-bar shaped corner member 9 are slotted inwardly from their vertical edges and material between slits is turned inward at right angles to the respective legs, forming a pair of lower tongues 11, a pair of intermediate tongues 12, and a pair of upper tongues 13, 80 corresponding to the spaces between the slats. The vertical dimension of each tongue is greater than the width of the space to which it corresponds; and the slats have gains 14 cut in their edges, receiving 85 the top or bottom end parts, as the case may be, of the respective tongues (Fig. 5). In the material of each leg between the turned in tongues, holes 15 are punched, through which rivets 16 pass, extending in 90 through the respective slats.

The inner corner member 17 (Fig. 3) also is pressed into the shape of an angle bar; and its top end is pressed inward to form the stacking guide 18, adapted to extend 95 above the upper edge of the crate, somewhat offset inwardly, when this inner member fits snugly against the inner sur-

faces of the slats, at a corner, with the plain lower end of this member 17 substantially flush with the lower edge of the crate. The rivets 16 pass through holes 19 in the inner corner members; and being headed inside and outside, bind the outer members 9 and inner members 17 firmly together, with the slats between them firmly held from up and down movement or endwise movement, not only by these rivets but by the tongues 11, 12 and 13 fitting snugly in the gains or recesses 14 of the slat edges. Also, this fitting of the tongues in the gains, as well as the fitting of the slat end parts together, prevents up and down weaving or diagonal distortion of the structure. The tongues 11, 12 and 13 preferably are as long transversely as the thickness of the slats, so that their inner edges abut the inner corner members 17. For finished appearance the inner member 17 has recesses 20 and 21 in its vertical edges, registering with the respective spaces between slats, so that the inner edges of these recesses 20 and 21 and the inner ends of the tongues 11, 12 and 13 come close together.

In the modification of Fig. 6 the only difference is that the slats 2', 3', and 4' of the side walls 1' and the slats 6', 7' and 8' of the end walls 5' are so wide that their edges are very close together or abutting. However, the middle parts of the lower edges of the top end slats 8' are recessed to form hand holes 22. Only parts of one end and one side of this modified crate or box are shown; but it will be understood that the remainder of the structure is similar to that shown. If ventilating openings are desired in the sides of the crate, edges of slats 40 may be recessed, as is well known in the art. In the example of Fig. 1, ample ventilation is afforded by spacing the slats apart, and a much lighter crate is thereby afforded, with considerable saving of lumber. This saving 45 is not merely proportional to the widths of the spaces; the narrower strips of lumber may be obtained at a much lower rate than the wider boards usually employed in such crates, as for example only one or two pieces 50 to a side or end. In the interest of economy and lightness, therefore, we prefer the narrow slat construction of Fig. 1; but even with the wider abutting boards or slats of Fig. 6, the lower cost of the narrow lumber 55 permits a saving. In either construction, the gains 14 of Fig. 1, or the gains 14' of Fig. 6, which are deeper due to the increased widths of the slats, are cut very rapidly with a cross-cut saw, or with two saws 60 spaced to cut the gains in both end parts of a strip at one passage. The sheet metal corner members 9 and 17 are readily formed by means of relatively simple tool equipment, and need not be of great thickness, as 65 is necessary in some prior corner reinforce-

ments in order to be effective. Thus we save both in the wood construction and in the metal corner attachment.

In Fig. 1 we have illustrated partially an interior bottle supporting construction well known in the art, comprising longitudinal and transverse partition rods 23 and 24, having their ends fastened in end wall and side wall slats, respectively, and longitudinal support rods 25 with their ends fastened 70 in the bottom slats 6 of the end walls. As shown, the outermost ones of these support rods pass through openings 25' and 25" in the bottom parts of the outer corner member 9 and the inner corner member 17, respectively. As these interior details are not essential parts of our invention, and any other suitable interior bottle supporting structure may be substituted in conjunction 75 with our improved wall and corner construction, most of each rod has been omitted, so as not to obscure the illustration of the inner corner construction in Fig. 1.

The effectiveness of the corner members, with the outer corner member tongues in the gains of the slats, to resist up and down weaving of the structure has been noted. Although the metal of the tongues is relatively thin, the tongues are able to resist that 80 action by virtue of their close fitting in the gains 14, so that for such movement to occur, the tongues must be twisted very close to their junctions with the main part of the member 9, where they have almost the full 85 reinforcement of the main part edgewise. This simple, comparatively light metal construction also practically prevents sidewise weaving, although the inner corner members have no diagonal bracing other than the 90 spandrel shaped top parts of their stacking 95 guide extensions 18 at their tops. Because a side slat, lapping across the end of an end slat, must swing out away from the gain 14 in the end slat, and is prevented from doing 100 this by the outer member 9 hugging the outside of the side slat closely and having its tongue firmly fitting in the end slat gain 14, the outer corner member 9 resists such 105 sidewise weaving in tension, at each corner 110 where this movement would result in reducing the angle between the end and side walls. 115

Of course such resistance as the inner members 17 have is added to the resistance of the outer members 9; and the inner members may have suitable diagonal bracing, as 120 for example, ribs such as shown and claimed in our copending application, Serial No. 8,906, filed February 13, 1925. But where omission of such interior bracing is desirable, to avoid obstruction to ready insertion 125 of bottles in the corner compartments of the crate, we provide for that without impairing the rigidity of the crate; and by doing this with metal in tension the required amount of metal is minimized, with the 130

benefits of lightness and economy before alluded to.

In a crate made up of relatively narrow slats or boards, either as in Fig. 1 or as in

5 Fig. 6, expansion or swelling of the wood up and down is amply compensated for, because the swelling of each narrow slat or board is not so great, and is not added to that of the other boards or slats, because of 10 the space between the boards or slats, even where these are close together as in Fig. 6. Having only one rivet at each end of a slat facilitates this, as the slat can swell each way from its rivet.

15 The crate is very readily assembled. By reference to Fig. 4 it will be seen that the side wall slat 3 may have its end brought in between the inner ends of the tongues 11 and 12 at the side and the inner surfaces of the 20 tongues 11 and 12 at the end, and then be pressed out in broadside direction, with the side tongues 11 and 12 entering its gains 14 as seen in Fig. 5. Then the end wall slat 7 simply is brought with its end against the 25 side wall slat, and pushed out, receiving the end tongues 11 and 12 in its gains 14. All of the corresponding slats thus are readily assembled with the corner members 9 in this manner; and then, after the inner members 30 17 are positioned, and a few of the rivets 16 inserted to hold these inner members in place, the crate is held assembled for completion of the riveting and securing of the interior bottle support rods 23, 24 and 35 25, or other equivalent structure, part or all of which may have been attached to the slats before assembling them with the corner members as above described.

40 Of course the number and dimensions of the slats may vary, and the number of tongues and other details of the corner members may vary accordingly, and numerous other modifications besides those alluded to herein may occur, as well as adaptation of 45 our improved construction to boxes, crates or the like for purposes other than containing milk bottles.

Therefore, we do not wish to be understood as being limited to the precise disclosure herein, but having thus fully described a preferred embodiment of our invention, as is required, what we claim as new and desire to secure by Letters Patent is:

50 1. In a bottle crate, upright wall members assembled to form a corner of the crate, each of oblong vertical cross-section with its narrow edges horizontal and having a transverse recess in one of said horizontal edges near said corner, said recess terminating short of the opposite narrow edge, and a corner member lapping around the corner outside said wall members and having extensions in the respective recesses.

55 2. In a bottle crate, a plurality of upright series of wall members assembled to form a

corner of the crate, each of oblong vertical cross-section with its narrow edges horizontal and having a transverse recess in one of said horizontal edges near said corner opening out toward the other member of the 70 series, said recess terminating short of the opposite narrow edge of the respective member, and a corner member lapping around the corner outside said wall members and having extensions one of which fits between the wall members of one series in the recesses thereof, and another of which fits between the wall members of the other series in the recesses thereof.

3. In a bottle crate, a plurality of upright 80 series of wall members assembled to form a corner of the crate, each having a recess in its horizontal edge near said corner opening out toward the other member of the series, and a corner member lapping around the 85 corner outside said wall members and having extensions, certain ones of which fit between the wall members of the respective series in the recesses thereof, and certain other of which extensions lie along the 90 outer sides of the respective wall members, these other extensions being secured to said wall members, beyond said recesses from said corner.

4. In a bottle crate, a plurality of upright 95 series of wall members assembled to form a corner of the crate, each of oblong vertical cross-section with its narrow edges horizontal and having a transverse recess opening out through its edge toward another member of the series near said corner, said recess terminating short of the opposite narrow edge of the wall member, and a corner member of sheet metal pressed into angle-bar shape and having its upright edges along the respective series of wall members slitted at intervals, alternate portions between slits being turned inward on lines longitudinal of the corner member, forming a series of extensions on the respective legs of the angle-bar shape, each extension of one of said series having its upper and lower end parts fitting in adjacent recesses of one of said series of wall members, and each extension of the other series having its upper and lower end parts fitting in adjacent recesses of the other series of wall members, and the remaining portions of said corner members between slits being fixed to the upright sides of the respective wall members.

5. In a bottle crate, upright wall members assembled to form a corner of the crate, members at one side of said corner being in upright series with their adjacent edges separated, leaving a space, each member of the series having a transverse recess in one of its horizontal edges near said corner opening out toward the other member of the series, said recess terminating short of the opposite narrow edge of the respective mem-

ber, an outer corner member lapping around the corner outside said wall members and having extensions one of which fits between said members of said series in the recesses thereof and extends substantially to the inner surfaces of said wall members, and an inner corner member fitting against the in-

ner surfaces of said wall members and secured thereto, and lapping close to the inner end of said extension at said inner surfaces, ¹⁰ to exclude foreign substances from the space between the corner members.

HERBERT H. GERDING.
EDWARD A. GERDING.
